[57] **CLAIM**

The ornamental design for a hanger, as shown and described.

DESCRIPTION

FIG. 1 is a front perspective view from above and one side of a hanger embodying the invention;

FIG. 2 is a rear view of the hanger shown in FIG. 1; and, FIG. 3 is a side view of the hanger shown in FIG. 1.

The bottom surfaces of the hanger follow the contours shown in FIGS. 2 and 3.

1 Claim, 2 Drawing Sheets Fig. 1.

Fig.2.

Fig.3.
